UNITED STATES PATENT OFFICE.

WILLIAM M. MORTON, OF NEW HAVEN, CONNECTICUT.

THILL-COUPING.

SPECIFICATION forming part of Letters Patent No. 653,689, dated July 17, 1900.

Application filed October 30, 1899. Serial No. 735,160. (No model.)

To all whom it may concern:

Be it known that I, WILLIAM M. MORTON, a citizen of the United States, and a resident of New Haven, in the county of New Haven and State of Connecticut, have invented certain new and useful Improvements in Thill-Couplings, of which the following is a specification.

My invention relates to an improvement in thill-couplings; and it consists in certain details of construction, to be more fully set forth in the following specification.

To enable others to understand my invention, reference is had to the accompanying drawings, in which—

15 Figure 1 represents a side elevation of the thill-coupling locked and broken view of the thill or shaft. Fig. 2 is a bottom plan view of the thill-coupling and broken view of the shaft. Fig. 3 represents a broken bottom view 20 of the thill-coupling and handle portion of the locking cam-lever, with said lever partially disengaged from the hinged eye-section. Fig. 4 is a broken bottom view of the thill-coupling with the locking cam-lever thrown to one 25 side to unlock the hinged eye-section. Fig. 5 is a broken view of the thill-coupling with the lever disengaged from the hinged eye-section and such eye-section dropped. Fig. 6 is a detail perspective view of the hinged eye-section.

The construction and operation are as follows:

1 represents the thill-iron, attached to the thill 2. Said iron has the semicircular head 2^a, adapted to partially embrace the shaft-bolt. (Not shown.)

3 (see also Fig. 6) is the eye-section, adapted, in conjunction with the head 2^a of the thill-iron, to form a complete eye.

40 4 is a semicircular seat formed in the upper surface of the said hinged eye-section, against which seat the end of the locking-lever, presently to be described, cams.

45 5 is a rearwardly-projecting tongue adapted to be inserted between the ears 6 6^a of the thill-iron, which tongue, combined with the hole 7 and the pin 8, pivotally connects said section with the head of the thill-iron.

50 9 is the locking-lever, pivotally supported on the pin 10, projecting from the thill-iron. 9^a is the head portion of said lever, provided with the cam-face 9^b, adapted to be engaged

or disengaged with the semicircular seat 4 of the hinged eye-section. The head portion 9^a is considerably thicker than the handle portion of said locking or cam lever, so as to provide a firm rear support for the hinged eye-section 3.

55 11 is the ordinary strap-loop, projecting from the thill-iron 1; but in this instance it 60 is provided with the projection 12, adapted to engage with the notch or opening 13 in the end of the locking-lever handle. 13^a are beveled portions of the side walls of said opening to provide means for disconnecting the 65 lever from the projection 12 of the loop 11. As before remarked, the handle portion of this locking-lever is much thinner than the head, for the reason that in locking or unlocking the same this thin portion is slightly 70 depressed or sprung down in the direction of arrow a, Fig. 1, to engage or disengage it from the projection 12.

75 Devices of this character have been made where the locking-lever is pivotally supported on a pin or stud projecting from the outer surface of the hinged eye-section. In such a construction when the coupling is locked the handle of the lever, lying as it does along the thill-iron, is fulcrumed on said thill-iron, and 80 the strain will have a tendency to open the hinged eye-section by reason of the fact that such handle portion must necessarily be made thin enough to be sprung over onto the thill-iron to lock the same. Therefore this strain 85 will partially open the coupling sufficient to produce rattling, if nothing more serious should happen. In my improved construction the strain, which is in the direction of arrow b, Fig. 1, is exerted against the cam 90 end 9^b of the lever, which in connection with the large stud 10 offers a resistance sufficient to prevent the slightest opening of the closed eye. Another advantage of this method of securing the said hinged section is that should 95 the handle of the lever become disengaged from its fastening it will hold such section if only a small portion of the cam end of said lever and the semicircular seat of the eye-section are engaged, as shown at Fig. 3, as nothing short of swinging such cam portion clear of said seat will release said eye-section, as shown at Fig. 4. The under surface of the head portion of the locking-lever also rests

on the horizontal surface 5^a of said eye-section. When the hinged eye-section is opened, as shown at Fig. 5, it is closed by simply swinging the locking-lever around to engage 5 the cam 9^d of said lever with the seat 4, which will carry such section up to close about the shaft-bolt.

From the forgoing description it will be observed that my device is simple of construction, easily and quickly operated, and very effective for the purpose for which it is adapted.

Having thus described my invention, what I claim as new, and desire to secure by Letters 15 Patent, is—

In a thill-coupling, of the character described, consisting, in combination with a

hinged eye-section, having a semicircular seat formed therein, of a swinging locking-lever pivotally supported on the thill-iron, a cam-face on the end of the head portion of said lever adapted to engage with said seat to close said eye-section and hold it firmly in place, means substantially as shown for securing the handle portion of said lever when the 25 hinged eye-section is closed all substantially as described and for the purpose set forth.

Signed at New Haven, in the county of New Haven and State of Connecticut, this 16th day of October, A. D. 1899.

WILLIAM M. MORTON.
